UNITED STATES PATENT OFFICE

EDGAR E. PAQUETTE AND ROLAND J. PAQUETTE, OF WOODSTOCK, ONTARIO, CANADA,
ASSIGNORS TO SCOTT & WILLIAMS, INCORPORATED, OF NEW YORK, N. Y., A CORPORATION OF MASSACHUSETTS

KNITTING MECHANISM

Application filed July 26, 1927. Serial No. 208,596.

This invention relates to circular knitting machines and more particularly to mechanism for making a stocking with a gusset between the narrowed and widened portions of the toe pocket. One object of the invention is to produce a machine in which the manipulations necessary to produce the gusset are obtained through the butts of the needles by mechanism which is independently operated and which is controlled without the necessity of using an additional cam path on the pattern drum. Another object of the invention is to provide such a mechanism which can be easily and simply adapted to the ordinary automatic seamless hosiery circular knitting machine of the revolving needle cylinder type. The invention will be shown and described in the well-known Scott & Williams circular knitting machine, such for instance as is shown in the patents to Robert W. Scott Nos. 1,152,850, dated December 7, 1915 and 1,282,958, dated October 29, 1918. The invention contemplates the use of different lengths of needle butts controlled by separate raising and lowering cams actuated from racking means which in turn are controlled by the so-called gravity rod controlling the widening picker and the switch cam as usual.

In the drawings,

Figure 1 is a view from the left side of a Scott & Williams machine showing the raising and lowering cams and the special mechanism for actuating them according to the invention, the parts being shown just prior to the insertion of the raising cam 11;

Figure 2 is a view similar to Figure 1 taken from the front of the machine;

Figure 3 is a plan view of the mechanism shown in Figure 1 showing some of the needle butts;

Figure 4 is a plan view of the control mechanism taken on the line 4-4 of Figure 1;

Figure 5 is a vertical section through the shafts carrying the narrowing and widening pickers, taken on the line 5-5 looking to the right as shown in that figure;

Figure 6 is a view similar to Figure 1

showing the parts at the moment when the locking pawl is idling over the low tooth;

Figure 7 is a detail elevation of the raising and lowering cams at the moment when the raising cam is inserted;

Figure 8 is a diagrammatic view of the foot of a stocking produced by the mechanism of this invention, showing the gusset; and

Figure 9 is a development of the cam cylinder showing the raising and lowering cams, the arrow showing the direction of movement of the needles when the cam 10 or the cam 11 is in action.

As above stated, the invention is concerned with mechanism for introducing a gusset such as is shown at C in the toe or D in the heel of Figure 8 between the narrowed and widened segments of the ordinary seamless heel or toe pocket, the mechanism being controlled through the medium of the usual gravity rod B (Figures 1 and 6). As in the ordinary Scott & Williams machine and the above-mentioned patents to Robert W. Scott Nos. 1,152,850 and 1,282,958, this gravity rod is controlled by a cam path on the usual main pattern drum (not shown) and operates the usual widening picker 680 and the switch cam 415 or its equivalent (Fig. 9). Raising and lowering cams 10 and 11, such as shown in the drawings of this application, are used in addition to the ordinary switch cam. The mechanism for controlling the narrowing and widening cams 10 and 11 is actuated from the rack wheel 35, which can conveniently be mounted loosely on the end of the pattern chain shaft, and a pawl 40 which receives its movement from a cam 44 carried by the main drive shaft 45 adjacent the main bevelled gear (not shown). This rack wheel 35 has thereon a low tooth over which the pawl 40 idles until the spring finger 46 fastened to the gravity rod B by screws 47 turns the rack wheel 35 until the pawl 40 rides off the blank tooth and starts turning the rack

wheel.

Referring to the drawings in detail, the needle cylinder A contains needles with butts of different lengths therein arranged in groups, the grouping in one-half of the

needle cylinder in the example shown in the drawings consisting of a group of needles having short butts flanked at either end by a group of needles having slightly longer butts and the outer ends of those groups coming at the median line of the cylinder and meeting there other needles having still longer butts. For the sake of convenience these butts will be termed short, medium and longer butts. Adjacent the needle cylinder at or near the usual point, lowering cam 10 and raising cam 11 are mounted on the bed-plate C of the machine by means of a U-shaped bracket 14. The shanks 12 and 13 of these cams 10 and 11 pass through both arms of the U-bracket 14 and have thereon between these arms stop collars 14a held with set screws 15 at the rear or radially outward end of the shanks 12 and 13. Between these stop collars 14a and the arm of the bracket 14 which is located nearest the cams 10 and 11 are compression springs 16 which have the effect of tending to urge the cams 10 and 11 radially outward. The radial movement of the cams 10 and 11 toward and away from the butts of the needles is obtained from the rear end of the shanks 12 and 13 through bell crank levers 18, 19 having upturned ends 20, 21 which engage against the outer ends of the shanks (Fig. 6). These bell crank levers 18, 19 are mounted on the bed-plate C by means of bearings 17 and are adapted to oscillate on their longitudinal axes by movements received from the rack wheel 35 through mechanism which will now be described. These bell crank levers 18, 19 have at their ends away from the upturned ends 20, 21 which engage against the outer ends of the shanks 13, outwardly bent arms or extensions 26, 27 pivoted to adjustable links 22, 23 which in turn are pivoted at 29 and 30 to levers 31, 32. The other ends of the levers 31, 32 are pivoted at 33 to a bracket 34 suitably secured to any stationary part of the frame of the machine. The adjustments in length of the links 22, 23 are made by means of slots and set screws 28 as shown in Figure 1. The levers 31, 32 are raised and lowered by cam means on the rack wheel 35, these cam means consisting of lifting lugs 49 and 50 secured against one side face of the rack wheel 35 by screws 51 and small pins 52. These lifting lugs are adapted on revolution of the rack wheel to engage against projections 47a and 48 on the lower edges of the levers 31 and 32 respectively, the bevels on the projections 47a and 48 engaging against a bevelled surface on the lifting lugs 49, 50. The rack wheel 35 is mounted loosely on the pattern chain shaft 38 as above mentioned by means of the retaining screw 37. The pawl 40 which racks the wheel 35 is carried by an arm 39 to which the pawl 40 is pivotally attached at 41. This arm 39 pivots about the same center as the rack wheel 35 and it

has at its outer end a pin 43 projecting sideways therefrom in the path of the cam 44 carried by the main drive shaft 45. The pin 43 is adapted to be held in contact with the cam 44 by means of a tension spring 42 stretched between the arm 39 and the bracket 34. The revolution of the cam 44 in either direction is adapted to swing the arm 39 to the right, as shown in Figure 1, i. e., toward the front of the machine, and to rack the wheel 35 forward one tooth for each reciprocation of the arm 39 except when the low tooth 36 comes under the pawl 40. The pawl then idles back and forth over this low tooth until the spring finger 46 on the gravity rod 80 advances the rack wheel. This advancement of the rack wheel by the gravity rod occurs when the gravity rod, having been raised a sufficient distance to bring the spring finger beyond the next tooth on the wheel 35, is lowered again to its lowermost position.

The construction of the machine having been described, its operation will now be set forth. Assuming that the machine has knit the foot and has completed the narrowed segments of the toe, the gravity rod which was raised at the beginning of the toe to lower the switch cam to the position shown in Figure 9 to raise the long butt needles, is lowered and the spring finger 46 engages one of the teeth of the rack wheel 35 and turns that wheel until the pawl 40 can engage the first tooth below the low tooth 36. The needle cylinder is of course moving in a reciprocatory manner at this time and therefore the cam 44 is turning first in one direction and then in the other, at the rate of one revolution per each revolution of the needle cylinder. Therefore at each oscillation of the needle cylinder the rack wheel 35 is advanced one tooth from the position shown in Figure 6 until the lug 49 comes into contact with the projection 47a on the lever 31, causing the latter to elevate the link 22 to move the end 20 of the bell crank lever 18 radially inward and put the cam 10 into position where it will engage with the medium butt needles in the two flanking groups shown in Figure 3 and the long butt needles also. The long butt needles are immediately lifted out again by the switch cam 415. The machine knits one oscillation or course with this lowering cam 10 in operative relation with the needle butts. This course corresponds with the line 53 of Figure 8. The next movement of the pawl 40 moves the lug 49 beyond the projection 47a, thus dropping the lever 31, the link 22 and the bell crank lever 18, retiring the lowering cam 10. This leaves the two groups of medium butt needles down in action and the continued operation of the machine knits the courses of the gusset. The machine knits about six courses with the lowering cam 10 and the raising cam 11 both retracted and the medium butt needles down in action, the

rack wheel turning about six teeth during this time. During these six courses the lifter picks 650 raise medium butt needles on alternate sides of the stocking on each stroke.

- 5 Then the lug 50 on the rack wheel comes into contact with the projection 48 on the lever 32 and acting through the link 32 of the bell crank lever 19 the end 21 of the bell crank lever pushes the raising cam 11 radially inward to its operative position. This raises the medium butt needles to idle position and the raising cam 11 remains in for one oscillation, thus making the stitches along line 54 in Figure 8, completing the gusset. The next 10 rack of the wheel 35 retires the raising cam 11 and also brings the low tooth 36 under the pawl 40, completing the cycle of operation of the rack wheel and the pawl. The rack wheel and pawl will now remain idle until the narrowed portion of the next pocket has been completed. The widening picker 680 then comes into action and the widened segment is made.

We claim:

- 25 1. In a circular knitting machine, a circle of independent needles having groups with butts of different lengths, and devices for gradually narrowing and widening by acting on the needle butts to make a pocket, in combination with means acting directly on the needle butts to lower and raise as units certain of said groups of needles for the purpose of producing a gusset between the narrowed and widened segments of the pocket.
- 30 2. In a circular knitting machine, a circle of independent needles having groups with butts of different lengths including two groups whose butts are distinguished from a group flanked by them, and devices for gradually narrowing and widening to make a pocket, in combination with cam means acting directly on the needle butts to lower and raise said flanking groups of needles as units for the purpose of producing a gusset between the narrowed and widened segments of the pocket.
- 35 3. In a circular knitting machine, a circle of independent needles having groups with butts of different lengths, and devices for gradually narrowing and widening a pocket by acting on the needle butts, pattern means controlling the making of the narrowed and widened segments, and independent means for acting directly on the needle butts to produce gussets between the narrowed and widened segments of the pocket, said independent means being put into action by said pattern means.
- 40 4. In a circular knitting machine, a circle of independent needles having groups with butts of different lengths, and devices for gradually narrowing and widening to make a pocket by acting on the needle butts, in combination with raising and lowering cams and

mechanism adapted to operate said raising and lowering cams independently of each other to produce a gusset between the narrowed and widened segments of a pocket.

5. In a circular knitting machine, a circle of independent needles having groups with butts of different lengths, devices for gradually narrowing and widening to make a pocket by acting on the needle butts, and pattern means controlling said narrowing and widening, in combination with a raising cam and a lowering cam acting directly on said needle butts, means for actuating said needle raising and lowering cams independently of said pattern means and means actuated from said pattern means to initially control said raising and lowering cam operating means.

6. In a circular knitting machine, a circle of independent needles having groups with butts of different lengths, a switch cam and pickers for gradually narrowing and widening to make a pocket by acting on the needle butts, in combination with independent lowering and raising cams for said needle butts, rotating cam means whose rotation is initiated by the devices for gradually narrowing and widening, said rotating cam means being adapted to insert and retract said lowering and raising cams for the purpose of producing gussets between the narrowed and widened segments of the pocket.

7. In a circular knitting machine according to claim 6, the provision of operating means for said independent raising and lowering cams, said operating means having separate tilting elements for actuating the raising and lowering cams.

8. In a circular knitting machine, a circle of independent needles having groups with butts of different lengths, and devices for gradually narrowing and widening to make a pocket by acting on the needle butts, in combination with independent raising and lowering cams acting directly on the needle butts to raise and lower medium butt groups as units, racking means controlling the time of insertion and removal of said raising and lowering cams and a cam operating in timed relation with the needle cylinder adapted to rack said wheel, and a rod forming part of the device for gradually narrowing and widening, said rod initially actuating said rack wheel to produce a gusset between the narrowed and widened segments of a pocket.

9. In a circular knitting machine, a circle of independent needles having groups with butts of different lengths, and a switch cam and pickers for gradually narrowing and widening to make a pocket by acting on the needle butts, in combination with independent lowering and raising cams adapted to lower and raise groups of needles as units, and control mechanism adapted to cause lowering of two lengths of butts by said lowering cam

and raising of one of the two lengths by said switch cam, for the purpose of producing a gusset between the narrowed and widened segments of the pocket.

In testimony whereof we affix our signatures.

EDGAR E. PAQUETTE
ROLAND J. PAQUETTE.
